Primary Examiner — Sheryl Lane*(74) Attorney, Agent, or Firm* — Woods Oviatt Gilman LLP; Katherine H. McGuire, Esq.(57) **CLAIM**

The ornamental design for a hand-held spreader, as shown and described.

DESCRIPTION

FIG. 1 is a perspective view looking downwardly from the right side of the front of a hand-held spreader in accordance with my design;

FIG. 2 is a right elevational view thereof;

FIG. 3 is a left elevational view thereof;

FIG. 4 is a front view thereof;

FIG. 5 is a rear view thereof;

FIG. 6 is a top view thereof;

FIG. 7 is a bottom view thereof;

FIG. 8 is a perspective view looking downwardly from the right side of the rear thereof; and,

FIG. 9 is a perspective view looking upwardly from the right side of the rear thereof.

The broken lines represent portions of the spreader and form no part of the claimed design.
